Patented Sept. 5, 1922.

Fig. 3.

Inventor:
Gust J. Dahl

UNITED STATES PATENT OFFICE.

GUST J. DAHL, OF SPUHN ISLAND, TERRITORY OF ALASKA.

KNOCKDOWN REVOLVING TABLE.

Application filed September 6, 1921. Serial No. 498,904.

To all whom it may concern:

Be it known that I, GUST J. DAHL, a citizen of the United States, residing at Spuhn Island, in the Territory of Alaska, have invented an improved and useful Knockdown Revolving Table, of which the following is a specification.

This invention relates to tables, and the primary object of my invention is a combination-improved-knock-down-revolving table that can be constructed in a practical and substantial manner, yet of light weight, without arms, beams and frames, and that can readily be kept clean and sanitary, and that will avoid the inconveniences such as special table-cloths, and the necessity of taking apart various devices for the exchanging of the table-cloths, etc., which generally accompany the use of self-waiting tables. Furthermore, the object is sought to obtain a combination-improved-knock-down-revolving-table that can be easily, simply, and economically manufactured, but that will be durable, efficient, easily moveable, useful for different purposes, and saleable at a low price to the user.

My invention consists of an improved double table in which one table or table top is superimposed over another, and to the underneath surface of the lower table are fastened four metal flanges, into which metal legs or standards are screwed. For the purposes of acquiring substantiality, without the necessity of using arms, beams or frames, the lower table is cross-veneered in such manner that two layers of wood are securely fastened together in immediate contact with the grain of the wood of each layer across and diagonal to the grain of the wood of the other layer, which prevents cracking and splitting. The lower table serves two purposes; first, it is a foundation for the mechanism and for the top or revolving table; second, it prevents dust, dirt and materials from the working mechanism falling into the dishes setting on, or on the table cloth of, the dining table. The top or revolving table is made substantial without the use of arms, beams and frames by the installation of a rim of wood or other substantial material in a groove to the depth of one-half inch on the under surface of the upper table and at a distance of one inch from its perimeter, and a molding is fast-

ened in place in the space between the edge of the upper table and said rim, which prevents cracking and splitting. This rim thus serves to strengthen and make the upper table substantial, and to conceal from view the lower table and the mechanism.

Figure I is a perspective view of my invention, supported on four short metal legs or standards with rubber tips, standing in place ready for use on an ordinary dining table. Figure II is a vertical view of the table as it appears when cut in half. Figure III is a top view of the upper side of the lower table. Similar reference figures and numerals designate similar parts in the different views.

As soon as the invention is placed on the market, sets of legs or standards of different lengths will also be marketed, for use in connection with its operation, which varying length of the legs will afford the user a choice as to the height that he desires the revolving table to come above the surface of the dining table or other object on which it is placed. The legs or standards are so constructed that they can be easily removed and one set interchanged for another set of different length, and the table converted from a low table to a high table or vice versa in a very few minutes without any laborious effort. In use, the set of legs of one inch length would place the revolving table in a position where it would practically rest upon the surface of the dining table, or other object on which it was placed, and would render unusable the space that will otherwise exist between the revolving table and the surface of the dining table or other object on which placed, as, for instance, when the set of legs of four inch length are used. When used in conjunction with a dining table six feet in diameter the revolving table should be three and one-half feet in diameter; thus leaving a free fifteen inch space around the perimeter of the dining table on which the plates, dishes, etc., actually used by the diner may remain in a stationary position, as on an ordinary dining table; whereas, such dishes, either with or without food, which are ordinarily passed or handed to the respective diners would be placed on the revolving table and any particular dish could thus be brought immediately adjacent or op-

posite to any diner. The revolving table may also be readily used for other divers purposes; for instance, by supporting it upon a set of long legs which rest on steel ball, ball-bearing casters, it becomes a convenient table for use in surgical operating rooms, offices, stores, libraries, shops, etc., as articles, instruments, merchandise, books, etc., can be placed upon it in divers positions and the 10 table revolved to bring the article in reach of the person desiring it without that person's having to change his position. I obtain these objects by the combination of the four metal legs with the improved mechanism and 15 the improved double table.

The improved connection shaft, 1, is screw-threaded at both ends. The upper end is screwed into the steel plate or ball-bearing, 7, and extends downward through a hole, 18, 20 in the lower table, 3, and revolves in the lower table and the lower steel plate or ball-bearing, 7. The improved connection shaft, 1, is also hollow, so that an electric cord, wire or medium may be run through 25 it and connected with an electric cooking plate, or such other electric utensil as may be desired to be used on the top surface of the table. The legs, 2, represent two of the 30 four metal legs or standards which support the table and are constructed from metal tubing with threads at both ends to permit the upper end to be screwed into the metal flanges, 13, which are securely fastened by bolts to the underneath surface of the lower 35 table, 3, which is cross-veneered in a substantial manner to acquire strength without the use of arms, beams and frames, by the superimposition of one layer of wood upon another in immediate contact with the grain 40 of the wood of each layer across and diagonal to the grain of the wood of the other layer. A rubber track, 4, is fastened to the upper surface of the cross-veneered lower table, 3, near its perimeter, to enable the 45 silent running therein of the steel ball, ball-bearing casters, 5, which are fastened to the underneath surface of the upper or revolving table, 20. The steel ball, ball-bearing casters, 5, come into contact with the rubber track, 4, only when the weight of the load placed 50 on the top of the revolving table, 20, is unequally distributed thereon. The plates or 55 bearings, 7—7, are two steel plates in each of which is a groove corresponding with the groove in the other plate, which groove is filled with steel balls, 6. The plate is then bored and the lower plate or bearing, 7, is secured to the center of the upper surface of the lower cross-veneered table, 3, and the 60 upper plate or bearing, 7, is secured to the center of the upper or revolving table, 20, by screws or bolts in such manner that the grooves of the plates or bearings, 7—7, directly oppose each other; thus rendering the 65 revolutions of the revolving table, 20, both

noiseless and free from friction. The nut, 8, is screwed on to the lower end of the connecting shaft, 1, and thus the nut, 8, and the shaft, 1, in combination, hold the revolving table, 20, and the cross-veneered lower table, 3, in juxtaposition to each other, except for a space of about one-quarter of an inch between their respective opposing surfaces in a manner so secure that the entire contrivance can be rolled on edge without anything coming apart, thus facilitating easy placement on or removal from an ordinary dining table or other object or surface on which it is desired to use it. The washer, 9, on the connecting shaft, 1, between the nut, 8, and the under surface of the cross-veneered lower table, 3, is to prevent binding. The rim, 10, of wood or other substantial material, is installed in a groove one-half inch in depth on the under-surface of the upper or revolving table, 20, and at a uniform distance of one inch from the perimeter of said upper or revolving table, 20. This serves a double purpose: in that, it strengthens the table, and also hides the mechanism and lower table from view. The screws or bolts, 11, which are four in number, secure the two plates or bearings, 7—7, to the respective surfaces of the upper and lower tables to which they are fastened. The rubber tips, 12, are screwed into metal reducers, 14, which in turn are screwed on to the lower ends of the legs, for the purpose of protecting from injury the surface of the dining table, or other object upon which the invention is placed. When the long legs, 2^a, are used, steel ball, ball-bearing casters are screwed to the lower ends of the metal reducers, 14. The four metal flanges, 13, are bored and threaded for the reception of the threads of the legs, 2, and the flanges, 13, are secured to the underneath surface of the cross-veneered lower table, 3, by the bolts, 15. The molding, 17, is fastened to the underneath surface of the upper or revolving table, 20, between the rim, 10, and the edge or perimeter of the revolving table, 20. The hole, 18, in the center of the lower bearing plate, 7, and the lower cross-veneered table, 3, is the aperture through which the improved hollow connecting shaft, 1, extends and revolves.

When the combination-improved-knock-down-revolving table is substantially constructed, combined and connected together as hereinbefore described, without arms, beams and frames, its weight will be so light that a child can lift and handle it, yet its strength will enable it to carry a load of a ton or more, and being thus entirely free from arms, beams and frames, it is neat in appearance and easy to keep clean, and can be rolled about on its edge on the floor or other surfaces from one point to another without coming apart; while in operation

it will revolve smoothly, steadily and noiselessly without binding, and equally as well when loaded as when no weight is upon it.

I claim:

- 5 The combination of a revolving table comprising a main section having top and legs, a revolving section having a top, with down-turned flanges at periphery thereof, a pivot pin connecting the centers of said sections, a ball bearing in two parts, one part attached to each section and surrounding said pivot pin, a circular track positioned near pe-
- 10

riphery and on the top of said main section, and balls mounted in bearings on the underside of the revolving top to roll on said track, all as substantially described.

In witness whereof, I have hereunto subscribed my name in the presence of two witnesses.

GUST J. DAHL. [L. s.]
